UNITED STATES PATENT OFFICE.

JOHN T. NESDALL, OF BROOKLYN, NEW YORK.

STAIR STRUCTURE.

1,113,368.

Specification of Letters Patent. Patented Oct. 13, 1914.

Application filed May 31, 1913. Serial No. 770,996.

To all whom it may concern:

Be it known that I, JOHN T. NESDALL, a citizen of the United States, residing at Brooklyn, in the State of New York, have 5 invented certain new and useful Improvements in Stair Structures, of which the following is a specification, reference being had therein to the accompanying drawing.

This invention relates to stair structures. 10 The primary object of my invention is to enable the components of the structure to be constructed at a factory, say, and then be set up at the point of use with a minimum of labor and without the requirement of skilled 15 workmen.

It is also an object of the invention to provide a stair structure that, when fabricated at the place of use, will retain stability and yet will be such that the components of 20 which it is constructed may be conveniently removed or replaced.

At the present day, in certain of the large cities, the building regulations are exceedingly stringent and require that stair structures, and especially in apartment-houses and the like, shall be constructed of metal and be such, in case of fire—which frequently centers at the stairway of a building—that such stair structures shall retain 30 a high degree of stability. It is well known that the stairs of a building are among the most expensive parts. In the erection of stair structures, it has been the aim to form the components thereof as cheaply as possible, and this is accomplished, for example, by stamping these components out of sheet metal. If the aforementioned building regulations are such that the riser-and-tread units of the structure must be of a prescribed 40 thickness, the difficulties of stamping out the parts are thereby greatly increased. To provide for this condition, I have devised a stair structure which includes a minimum of components, and these components are so 45 formed that, while the bending operations are comparatively few, yet, when the structure is fabricated, it is stable and rigid, and such stability and rigidity are accomplished without the use of bolts or other like securing 50 instrumentalities.

The invention comprises, in one aspect, a combined tread-and-riser unit so formed that, with a minimum of skill and labor, it may be placed in position between a pair of

stringers and self-locked (so to speak) with 55 said stringer.

In another aspect of the invention, it resides in certain novel details of construction and arrangement, all as hereinafter more particularly described and claimed. 60

The accompanying drawings, referred to herein and constituting a part hereof, illustrate a preferred embodiment of the invention, the same serving in connection with the description herein to explain the principles 65 of the invention.

Referring to these drawings: Figure 1 is a view in perspective, and somewhat fragmentary, of a portion of a flight of stairs, certain of the parts being broken away more 70 clearly to show structure which would otherwise be hidden; Fig. 2 is a view in perspective of one of the combined tread-and-riser units; Fig. 3 is a view in vertical cross-section of one of these units; Fig. 4 is a fragmentary view, partly in elevation and partly in vertical section, showing the manner of attaching such units to the stringers; Fig. 5 is a fragmentary view, in horizontal section on the line 5—5, Fig. 4; Fig. 6 80 is a fragmentary view in sectional elevation of a modified form of structure, the modification in this instance residing in the form of the riser-attaching means; Fig. 7 is a similar view of another modified form of 85 structure, the modification in this instance residing in the form of the tread-attaching means, and Fig. 8 is a fragmentary view in sectional elevation of a portion of one of the stringers, in modified form, showing the 90 slotted angular portion thereof.

In the embodiment illustrated in the accompanying drawings by way of example, the stair structure is shown as including a pair of stringers each provided with a 95 slotted angulated unit-supporting flange, and a series of combined tread-and-riser units, each unit including a tread-portion provided with an elongated anchoring and strengthening flange adapted to engage in 100 certain of said slots, and the riser-portion being provided with a rearwardly extending flange and with pendant lugs adapted to rest upon said stringer-flange and to extend through certain of the slots therein. The 105 different units are entirely independent of each other in the sense that they are unconnected one with another so that any one

or another of these may be removed or replaced without disturbing in any way any other of the units. At the same time, the units are attached to the stringers in such 5 a manner that they are, for all intents and purposes, absolutely rigid therewith.

The stringers 1 are formed, preferably at their lower edges, with an angulated flange or portion 2. This flange is provided with incuts or slots 3 and 4, these being in spaced relation, and arranged in pairs, each pair being (in the embodiment illustrated in Figs. 1 to 7) separated by an elongated portion 2^a of the flange, as 15 shown in Fig. 4.

In Fig. 8, a somewhat modified form of stringer is illustrated, and in this instance the angulated portions 2^b are formed only at the place where the units are to be secured.

20 Adapted to be supported between each pair of stringers is a combined tread-and-riser unit 5. This unit includes, preferably, a substantially horizontal tread-portion 6, provided with a pendant flange 7 which, 25 preferably and as shown, is of approximately the same length as the riser 6 and is adapted to extend through the slots 3 in the stringer-flange 2. Ordinarily, this flange 7 will constitute a substantial anchoring 30 instrumentality for securing the unit, at its upper portion, to the stringers. If, however, it be desirable to provide for additional securing, said flange may be angulated to form a portion 7^a, as shown in 35 Fig. 7, that is to say the lugs may, after the units are placed upon the stringers, be bent to an angle to form said angulated portion 7^a. The unit 5 also comprises a substantially vertical riser-portion 8 which, at its 40 lower end, is provided with a rearwardly extending angulated flange 9 and with two angulated lugs or extensions 10 which are adapted to extend through the slots 4 in the stringer-flange 2 and, thus, constitute 45 anchoring instrumentalities for securing the lower portion of the units 5 to the stringers. The flange 9 may, if desired, rest upon the section 2^a of the stringer flange 2 and thereby aid in supporting the unit at this point. 50 Ordinarily, this form of structure is sufficient to effect a rigid securing of the lower portion of the unit to the stringer; yet, if additional securing is desired, the lugs 10 may be bent or otherwise formed 55 (after the tread-and-riser unit is placed upon the angulated portion of the stringer) to provide an angular portion 10^a as shown in Fig. 6.

In fabricating my improved form of stair structure, the stringers 1, 1 will be set up and secured in any desired manner, and with the flanges 2 on each extending inwardly and toward each other, as shown in Fig. 1. The tread-and-riser units—having previously been formed—are then con-

veniently placed in position, and this is accomplished by inserting the flange 7 and the lugs 10 through the slots 3 and 4, respectively. This may be done simultaneously, or the flange 7 may first be hooked into the slot 3 and then the anchoring lugs 10 positioned in the slots 4. It is to be understood that I may rely upon the inherent resiliency of the metal of which the units are constructed to aid in holding these units in position; and, to this end, the free ends of the riser-portion 8 and the tread-portion 6 may be so preformed that a slight springing thereof will be necessary in order to permit the positioning of the flange 7 and the lugs 10 in their respective slots, whereupon the units will be more effectively retained in position by reason of the inherent resiliency of the metallic units. If, then, it be also desirable to effect a more 85 rigid attachment of the tread-portion 6, the flange 7 may be bent up against the lower face of the stringer-flange 2, as shown in Fig. 7, though it is to be understood that this bending may be done before the units are placed in position. Likewise, the lugs 10 may be bent, as shown in Fig. 6.

From the foregoing, it will be understood that the various components and instrumentalities, singly and in their coöperation, 95 contribute to effect a reliable and stable stair structure, and that a construction has been provided which realizes the objects of the invention and the advantages herein set forth, together with other objects and advantages.

The invention in its broader aspects is not limited to the particular construction shown, nor to any particular construction by which it has been or may be carried into 105 effect, as many changes may be made in the construction without departing from the main principles of the invention and without sacrificing its chief advantages.

What I claim is:

1. A stair-structure including two components, one of these being a pair of stringers provided with supporting sections integral with the body of the stringer; the second component comprising a combined riser-and-tread unit, the riser-portion thereof being provided with an anchoring flange adapted to engage with and rest upon the supporting section of the stringer, and the tread-portion thereof being also provided 115 with a strengthening flange adapted to extend over and rest upon a supporting section of the stringer; the tread-and-riser unit being supported on said stringer independent of any other tread-and-riser unit 120 thereon.

2. A stair-structure including two components, one of these being a pair of stringers provided with spaced supporting sections integral with the body of the stringer; 130

the second component comprising a combined riser-and-tread unit, the riser-portion thereof being provided with an anchoring flange adapted to engage with and rest upon the supporting section of the stringer, and the tread-portion thereof being also provided with a strengthening flange adapted to extend over and rest upon a supporting section of the stringer; the tread-and-riser unit being supported on said stringer independent of any other tread-and-riser unit thereon.

3. A stair-structure including two components, one of these being a pair of stringers 15 provided with spaced supporting sections integral with the body of the stringer; the second component comprising a combined riser-and-tread unit, the riser-portion thereof being provided with a plurality of pendant anchoring portions adapted to extend over and rest upon said supporting sections of the stringer, and a riser-strengthening flange integral with the body of the riser, and the tread-portion of the unit being provided with a strengthening and anchoring flange adapted to extend over and rest upon a supporting section of the stringer; the tread-and-riser unit being supported on said stringer independent of any other tread-and-riser unit thereon.

4. A stair-structure including, as components, a stringer provided with an integral angulated unit-supporting portion divided into sections, and a combined tread-and-riser component, said component being provided with integral stringer-attaching means including portions angulated with respect to each other, some of which portions extend over and rest upon the sections 40 of said unit-supporting portion of the stringer.

5. A stair-structure including as one component a pair of stringers each provided with an angulated unit-supporting portion, 45 and a series of combined tread-and-riser units adapted to rest upon said stringers one entirely independent of the other, and formed with integral means adapted to engage and rest upon the angulated portions 50 of the stringer, said means including a plurality of flanges occupying relatively different planes and adapted to project through said stringer portion whereby said units may be removably attached to the stringers.

55 6. As an article of manufacture, a combined tread-and-riser unit for stair-structures including a substantially vertical riser-portion provided with an angulated flange and a plurality of pendant anchoring lugs, 60 said lugs being arranged in juxtaposition to and at an angle to said angulated flange, and a substantially horizontal tread-portion provided with a pendant anchoring-flange.

7. As an article of manufacture, a combined tread-and-riser unit for stair-struct-

tures including a substantially horizontal tread-portion provided with a pendant anchoring flange, and a substantially vertical riser-portion provided with an angulated instrumentality extending from the rear face 70 of said vertical portion and in the direction of said flange on the horizontal portion, said vertical portion being also provided with a plurality of pendant lugs arranged in a plane substantially parallel with said vertical portion.

8. A stair-structure including in combination, a pair of stringers each provided with an integral angulated unit-supporting portion, said portion being formed with a series 80 of slots; and a combined tread-and-riser unit adapted to be positioned between the stringers, said unit comprising a substantially horizontal tread-portion provided with a pendant flange adapted to project 85 through certain of the slots in said angulated portion of the stringer, and a substantially vertical riser-portion formed with a rearwardly extending flange adapted to rest upon said angulated portion of the 90 stringers and provided with a plurality of integral pendant lugs adapted to extend through certain of the slots in said angulated portion, the different tread-and-riser units disposed between said stringers being 95 entirely independent one of the other.

9. A stair-structure including a pair of stringers each provided with an integral angulated flange formed with a series of slots, and a series of tread-and-riser units 100 adapted to be disposed between said stringers and entirely independent of each other, each unit comprising a substantially horizontal tread-portion provided with a pendant anchoring flange adapted to extend 105 through certain of the slots in said stringer-flange to secure the tread-portion of the unit thereto, and a substantially vertical riser-portion provided with a rearwardly extending flange occupying a position at an 110 angle to the riser-portion and paralleling the stringer-flange, said riser-portion also being provided with a plurality of angulated lugs occupying a position substantially parallel with said riser-portion and 115 at an angle to said stringer-flange and constituting a means for securing said riser-portion to the stringer.

10. A stair-structure including, as components, a stringer comprising a body-portion 120 and a recessed integral angulated unit-supporting portion extending longitudinally of the body-portion, and a combined tread-and-riser unit provided with integral stringer-engaging and attaching means including a plurality of portions arranged in angular relation with respect to each other, some of the portions being adapted to extend over and rest upon said unit-supporting portion of the stringer and other pend- 125 130 135

ant portions engaging in the recesses of the angulated portion of the stringer.

11. A stair-structure including, as components, a stringer formed with an integral 5 angulated unit-supporting portion provided with slots, and a combined tread-and-riser unit provided with a plurality of integral portions angulated with respect to each other, certain of which portions rest upon

and are sustained by said unit-supporting portion while other pendant portions extend into said slots.

In testimony whereof I affix my signature in presence of two witnesses.

JOHN T. NESDALL.
